UNITED STATES PATENT OFFICE.

CHARLES A. TOWNSEND, OF CANANDAIGUA, NEW YORK.

CAMP TOILET.

Application filed April 9, 1923. Serial No. 630,794.

To all whom it may concern:

Be it known that I, CHARLES A. TOWNSEND, a citizen of the United States, residing at Canandaigua, in the county of Ontario and State of New York, have invented certain new and useful Improvements in Camp Toilets, of which the following is a specification.

The object of this invention is to provide a new and improved type of collapsible camp toilet that can be quickly set up or knocked down and carried about in its collapsed form as a comparatively small package.

This and other objects of this invention will be fully illustrated in the drawing, described in the specification and pointed out in the claims at the end thereof.

In the accompanying drawing:

Figure 1 is a perspective view of the camp toilet with a portion of the tent covering it partly broken away.

Figure 2 is a vertical sectional view of one of the locking joints between two of the upright sections forming the support of the camp toilet.

In the several figures of the drawing, like reference numerals indicate like parts.

The camp toilet, forming the subject matter of this invention is intended for campers who travel in automobiles and erect a temporary camp when and wherever they find a suitable spot for such a camp. For this reason the camp toilet is so constructed that it can be carried about as a small parcel and when needed can be quickly erected and afterwards also quickly knocked down.

As illustrated in the drawing, the camp toilet comprises an upright 1 that is made up of three channel shaped sections 2, 3 and 4. These channel sections are made to telescope into each other and when extended as illustrated in Figure 1 are locked in their extended position by means of the spring dogs 5 and 6. The spring dog 5 is mounted on the back of the channel section 2 near the top thereof and the pin 7 carried thereon is adapted to engage through the hole 8 provided near the top of the lower channel section 2 into the hole 9 provided near the bottom of the upper channel section 3. The engagement of the pin 7 into these two holes locks the section 3 to the end of the sec-

tion 2. A similar locking arrangement is provided between the ends of the channel sections 3 and 4.

At the top of the channel section 4 a pair of horizontal brackets 10 and 11 are formed to project laterally from this channel section. To the outer end of each of these brackets is pivoted an arm 12 that can be swung into the horizontal position illustrated in Figure 1. On top of each of the arms 12 is pivoted a second arm 13 having an angular extension 14 formed thereon at the inner end thereof. The arms 13 are adapted to be swung laterally into an angular position with relation to the arms 12 to which they are pivoted as illustrated in Figure 1. In this position the angular extension 14 is adapted to project into a slot formed by the bracket 11 and another bracket 15 mounted above the bracket 11 and parallel thereto. The engagement of the angular extension 14 of the arm 13 under the bracket 15 operates to lock both the arm 12 and the arm 13 in the extended horizontal position illustrated in Figure 1.

After the upright 1 is erected, a suitable canvas tent 16 is adapted to be placed over the arms 12 and 13. The sides, end and front of this tent are provided with suitable anchoring pins or stakes 17 with which the sides, end and front of the tent can be anchored to the ground to provide sufficient room on the inside thereof as illustrated in the drawing. The front of the tent is slit to provide an entrance to the tent and the two sections of the front formed in this way may be hooked together on the inside of the tent by means of suitable locking means.

The lower end of the channel section 2 of the upright 1 is anchored in the ground by means of the sliding stake 18. This stake is mounted on the back of the channel section 2 and is held in place thereon by means of two sleeves 19 and 20. These sleeves may be struck up from the back of the channel section and form an integral part thereof.

Besides the stake 18 the upright 1 is also provided with a pair of horizontal supporting arms 21 and 22. These arms are pivoted to the side of the channel section 2 and in their laterally extended position illustrated in Figure 1, rest against the under side of the lugs 23 struck up from the sides of the

channel section 2. When therefore the upright 1 is anchored to the ground by means of the stake 18 and the arms 21 and 22 have been swung into the horizontal position illustrated in the drawing the arms form a substantial base for the upright which with the help of the stake hold the upright in its perpendicular position.

On the channel section 2 is provided the seat which is formed by two horizontally extending arms 24 and 25. These arms are mounted on the outer ends of the shaft mounted in the bearing 27. The bearing 27 is struck up from the back of the channel section and allows the arms to swing down on the sides of the channel section until the arms rest on the lugs 28 formed on the sides of this section. The lugs 28 then hold the arms in the horizontal position to form the seat.

As pointed out above, the channel sections and the parts mounted thereon are collapsible. Thus the three channel sections are made to telescope into each other. The arms 13 can be swung so as to lay parallel to the arms 12 and also allow these arms with the arms 13 to swing down against the side of the collapsed channel sections.

The arms 24 and 25 forming the seat are made to swing up against the sides of the channel section. The same is true of the arms 21 and 22 that can be swung up against the side of the channel sections below the arms 24 and 25. The sliding stake 18 can slide up on the back of the channel section and in that way all of the extendible parts of the upright can be folded up so that all of the parts of the upright make a parcel that is not much larger than the channel section 2 alone.

The outer ends of the arms 12 and 13 may be padded with a piece of rubber hose that is slipped over the free end of these arms or any other suitable padding may be provided thereon.

I claim:

1. In a camp toilet, the combination of an upright formed of three sections adapted to telescope into each other, a pair of arms hinged to the upper section of said upright, a second pair of arms pivoted on said first pair of arms near the hinged end and extending forwardly and outwardly, extensions formed on the inner ends of said second pair of arms, a pair of spaced brackets mounted on each side of the top of the upper section of said upright, said first pair of arms being hinged under the lower brackets, said extension of said second pair of arms being adapted to engage between the pairs of brackets and hold said first and said second pair of arms in a horizontal position with relation to said upright, a tent supported by said upright and said two pairs of arms.

2. In a camp toilet, the combination of an upright formed of three sections adapted to telescope into each other, a pair of arms hinged to the upper section of said upright, a second pair of arms pivoted on said first pair of arms near the hinged end and extending forwardly and outwardly, extensions formed on the inner ends of said second pair of arms, a pair of spaced brackets mounted on each side of the top of the upper section of said upright, said first pair of arms being hinged under the lower brackets, said extension of said second pair of arms being adapted to engage between the pairs of brackets and hold said first and second pair of arms in a horizontal position with relation to said upright, a tent supported by said upright and said two pairs of arms, spring pressed locking dogs mounted on said telescoping sections, said spring pressed locking dogs being adapted to lock said telescoping sections together in their extended position.

In testimony whereof I affix my signature.
CHARLES A. TOWNSEND.
